UNITED STATES PATENT OFFICE.

PETER JOHNSEN, OF NEW ORLEANS, LOUISIANA, ASSIGNOR OF ONE-HALF TO CLAUDE L. JOHNSON, OF NEW ORLEANS, LOUISIANA. **BEST AVAILABLE COPY**

FUEL INJECTION DEVICE.

Application filed December 8, 1924. Serial No. 754,641.

To all whom it may concern:

Be it known that I, PETER JOHNSEN, a citizen of the United States, residing at New Orleans, in the parish of Orleans and 5 State of Louisiana, have invented new and useful Improvements in Fuel-Injection Devices, of which the following is a specification.

This invention relates to inspirators for 10 internal combustion engines, and more especially to improve means for supplying liquid fuel into the combustion chamber at the desired period in the cycle of the engine.

15 The primary object of the invention is to provide an inspirator, in which the fuel is delivered under a high velocity to the chamber through a delivery nozzle having mounted therein a spray tip formed with spiral 20 grooves, so that the fuel will be divided into capillary streams and given a turbulent motion, thus insuring a complete vaporization of the product of combustion without detonation or fluctuation in the operation of the 25 engine.

A further object of the invention consists in the particular manner of operatively connecting the fuel delivery plunger to the fuel pump so that the stroke of the plunger and 30 the supply of fuel being delivered to the inspirator may be simultaneously varied, depending upon the load or the particular use to which the engine is to be applied.

Referring to the drawings, wherein is set 35 forth several preferred embodiments of the invention:

Figure 1 is a side elevational view of an internal combustion engine with my invention attached thereto.

40 Figure 2 is a front end view of Figure 1.

Figure 3 is a vertical sectional view of the inspirator showing the same mounted on the cylinder head of the engine.

45 Figure 4 is an enlarged sectional detail view of the lower portion of the delivery nozzle.

Figure 5 is a plan view of the spray plug.

Figure 6 is a detail sectional view of the drive shaft showing the manner in which 50 the fuel pump cams are connected thereto.

Figure 7 is a sectional view taken substantially along the line 7-7 of Figure 6.

55 Figure 8 is a side elevational view, with parts in section, of a modified form of the invention.

Figure 9 is an enlarged plan view of Figure 8, and

Figure 10 is a detail view of the slide-cam shown in Figure 9.

Referring to the drawings, in which like numerals designate like parts in the several views, 10 denotes an internal combustion engine which, for the purpose of illustration, is conventionally shown of the two cycle type, having three cylinders 11, and a fly 65 wheel 12 secured to the crank shaft 13 of the engine.

The head 14 of each of the cylinders 11 has an orifice 15 for receiving an inspirator 70 16. The downward movement of the inspirator in the cylinder is limited by a flange 17 through which extend the bolts 18 for securing the device to the engine. The inspirator preferably consists of a delivery nozzle 19 having an axial bore 20 and a conical seat 21 formed adjacent its lower end, which communicate with the combustion chamber of the engine through the restricted port 22, as shown in Figure 3. Positioned 75 within the bore 20 is a sleeve 23, preferably 80 of bronze, which has at its upper end an annular groove 24 communicating with a spiral or tortuous passage 24'. A fuel supply pipe 25 communicates with the annular groove 24 through an opening 26, while the opposite extremity of the passage 24' connects with radial ports 27 in the lower end of the sleeve so as to deliver the fuel from the supply 25 to a chamber 29. A spray plug 85 or tip 30, preferably tapered at its lower 90 end, snugly fits in the seat 21, and has a central opening 31 in the top thereof, which communicates with a series of spiral grooves 33 by means of the inclined ports 34, preferably four in number, as shown in Figure 5. 95 The top of the plug 30 engages the adjacent lower end of the sleeve and is maintained in position thereby, while the tapered portion fits into the seat 21 so as to preclude the possibility of the fuel seeping or dripping past 100 the plug.

A reciprocating plunger 35, having an enlarged head 36, extends within the sleeve 23, and is slidably maintained in position by a packing 37 and a gland 38 which fit in a 105 threaded counterbore 39 in the nozzle 19. The plunger 35 is normally forced upwardly, preferably by a coil spring 40 interposed between the head 36 and the adjacent face of the gland 38. 110

A laterally projecting arm 41 extends upwardly from one side of the nozzle 19 and has pivoted thereto, as at 42, an operating lever 43. One end of the lever 43 is arranged to contact with the head 36 of the plunger and is preferably provided with a vertical opening, through which extends a threaded bolt 44 that may be adjusted so as to vary the tension of the spring 40. The 10 opposite extremity of the lever 43 has a recess socket 45 in the underside thereof which receives the adjacent curved end 46 of a push rod 47 movably connected to the side of each of the cylinders by the clamp 48 and the guide lug 49. The lower end of the push rod 47 is preferably forked, as at 50, and has journalled therein a roller 51, which contacts with a longitudinally tapered cam 52 keyed to the shaft 53.

15 A suction pump 54 for each of the cylinders 11 delivers the fuel from any suitable point of supply to the pipes 25, where it is conducted through the port 26 and the tortuous passage 24' to the chamber 29 formed in the lower end of the sleeve between the spray plug 30 and the plunger 35.

20 As there is a separate pump delivering to each cylinder, their number will vary, depending upon the number of cylinders of the engine. Preferably the pumps 54 will be closely positioned with respect to each other, as shown in Figure 1. Each of the pumps 54 has an outwardly projecting piston or plunger 55, which controls the inlet 25 and outlet supply of fuel to the pump, and is arranged to contact with adjacent cams 56, 57 and 58 carried by the sleeve 59 on the shaft 53. The cams 56, 57 and 58 are preferably longitudinally tapered and are of the 30 same number as the cylinders of the engine. The outer cam 56 is keyed to a rib 60 and is adjustably connected to the operating collar 61 by means of a dowel pin 62 arranged to be selectively inserted in the opening 63 formed 35 in the adjacent faces of the cam and the collar. The cams 57 and 58 are similarly provided with complementary openings which receive dowel pins so that each of these cams may be adjusted rotatably relative to each other for selectively varying the 40 delivery of fuel to the several cylinders. A nut 64 threaded to one end of the sleeve 59 secures the cams 56, 57 and 58 in fixed position on the shaft 53, and may be readily removed therefrom for the purpose of permitting the cams to be adjusted.

45 A shaft 65 slidably mounted in the brackets 66 on the engine carries the spaced arms 67 which are provided with the sleeves 68 having set screws 69 that engage the shaft for adjustably securing the arms thereon. The upper ends of each of the arms 67 is preferably forked, as at 70 so as to engage complementary grooves 71 in each of the tapered 50 cams 52 and the collar 61, so that upon mov-

ing the rod 65 longitudinally the contact of the cams with the rollers 51 and the plungers 55, will be simultaneously varied. While the rod 65 is arranged to be manually operated, the same may be connected to a 70 part of the engine so as to be mechanically controlled.

A bracket 72 secured to the side of the engine by the bolts 73 supports the shaft 53, which shaft is rotatably connected to the 75 crank shaft 13 in any suitable manner, such as by the silent chain 74.

As a heavy grade of fuel is usually employed in the type of engines to which the inspirator is applied, the pump 54 is preferably provided with a drain cock 75, while a primer 76 on the supply pipe 25 receives the lighter fuel such as gasoline for initially starting the engine, the heavy fuel tending to force the gasoline into the cylinder where it is quickly ignited by the spark plug 77.

80 The operation of the device is as follows:

Assuming the engine to be in operation, the plunger 35 will force the fuel from the chamber 29 through the grooves 30 of the spray plug into the combustion chamber at predetermined intervals. If it is desired to vary the stroke of the plunger, due to change of load, the shaft 65 is moved longitudinally so as to either increase or decrease the stroke of the plunger as may be desired, and simultaneously therewith, the supply of fuel from the pump 54 and the nozzle 18 will be proportionately varied. Furthermore, should it be necessary to vary the supply of fuel to the several cylinders, this may be readily accomplished by selectively adjusting the tapered cams 56, 57 and 58 relative to each other.

85 The modified form of the invention illustrated in Figure 8 is substantially similar in operation to that previously described, with the exception that the inspirator 78, which is mounted on the cylinder head 79 of the engine, has a supporting arm 80, to which is pivoted at one end an operation lever 81, as at 81'. The lever 81 has an opening therein, through which extends the reciprocating plunger 82 which forces the fuel into the combustion chamber at the proper period in the cycle of the engine. The opposite end of the arm 81 is preferably forked and has journalled therein a roller 83 which engages the longitudinally tapered cam 84 keyed to the shaft 85, as at 86 but arranged to be slidably thereon. The cam 84 is operatively connected to a fuel pump, not shown, through the instrumentality of a forked arm 87, which engages the complementary groove 88 in the adjacent wall of the cam 84 so as to permit the contact surface of the cam 84 with the roller 83 to vary upon the cam being moved longitudinally relative to the shaft 85.

90 The lever 81 between its ends is provided

with a swell portion 89 which engages the underside of the plunger head 90. A coil spring 91 positioned between the plunger head 90 and the plate 92 normally tends to 5 force the plunger downwardly against the action of the lever 81, while an adjustable screw 93, which extends through an opening in the cap 94 is provided to vary the tension of the spring 91 when the same is 10 found desirable.

It will be seen that upon the rotation of the cam 84, the adjacent end of the lever 81 will descend, thus allowing the spring 91 to press the plunger 82 downwardly, 15 which in turn forces the fuel through the nozzle in the manner as previously described. Obviously, the timing of the reciprocating plunger is such that the delivery of the fuel to the combustion engine will occur at the 20 proper moment in the cycle of the engine which may be readily controlled and varied by the actuation of the cams, depending upon the particular kind of work with which the engine is to be used or the grade of fuel 25 being employed.

By reason of the particular formation of the spray plug 21, the fuel is forced into the combustion chamber of the engine in capillary streams and giving a turbulent 30 motion, thus insuring proper combustion and atomization of the fuel without danger of detonation. Furthermore, as the spiral grooves 25 are protected by the adjacent tapered wall of the nozzle, the formation 35 of carbon deposits thereon is prevented, while the probability of carbon collecting on the lower end or tip of the plug is practically precluded, due to the velocity with which the fuel is forced through the grooves 40 into the combustion chamber.

It is to be understood that the several forms of the invention herewith shown and described are merely illustrative, and in no sense restrictive, and that such changes as 45 fall within the purview of one skilled in the art may be made without departing from the spirit of the invention and the scope of the appended claims.

I claim:

1. In combination with a cylinder of an internal combustion engine, of an inspirator communicating with the interior of said cylinder, a reciprocating plunger in said inspirator for forcing the fuel into said cylinder, a fuel pump delivering to said inspirator, a common drive means operatively associated with said fuel pump and inspirator for delivering fuel to the engine at predetermined intervals, and means for simultaneously varying the quantity of fuel to the inspirator and the stroke of the plunger.
2. In combination with a cylinder of an internal combustion engine, of an inspirator communicating with the interior of said

cylinder, a reciprocating plunger in said inspirator for forcing the fuel into said cylinder, a fuel pump delivering to said inspirator, a common drive means operatively associated with said fuel pump and inspirator for delivering fuel to the engine at predetermined intervals, and slidable means for simultaneously varying the quantity of fuel to the inspirator and the stroke of the plunger.

3. The combination with the cylinder of an internal combustion engine, of an inspirator communicating with the interior of said cylinder, a reciprocating plunger in said inspirator for forcing the fuel into said cylinder, a lever pivoted to said inspirator and engaging said plunger, a push rod connected to said lever, a fuel pump delivering to said inspirator, and a common drive means operatively associated with said push rod and pump for forcing the fuel to said inspirator at predetermined intervals.

4. The combination with the cylinder of an internal combustion engine, of an inspirator communicating with the interior of said cylinder, a reciprocating plunger in said inspirator for forcing the fuel into said cylinder, a lever pivoted to said inspirator and engaging said plunger, a push rod connected to said lever, a fuel pump delivering to said inspirator, and longitudinally tapered cams operatively associated with said push rod and pump for forcing fuel through said inspirator at predetermined intervals, and slidable means connected to said cams for simultaneously varying the supply of fuel to the inspirator and the movement of the plunger.

5. The combination with the cylinder of an internal combustion engine, of an inspirator communicating with the interior of said cylinder, a reciprocating plunger in said inspirator for forcing the fuel into said cylinder, a lever pivoted to said inspirator and engaging said plunger, a push rod connected to said lever, a fuel pump delivering to said inspirator, a shaft mounted on said engine, a cam keyed to said shaft and contacting with the lower end of said push rod, means for rotating said shaft, a second cam on said shaft, said pump having a yieldable member contacting with said last mentioned cam, means for rotating said shaft, and means for simultaneously varying the stroke of the plunger and the supply of fuel from the pump to said inspirator.

6. The combination with the cylinders of an internal combustion engine, of an inspirator mounted on each of said cylinders and communicating with the interior thereof, a reciprocating plunger in said inspirator, a lever pivoted to said inspirator and contacting with said plunger, a push rod connected to said lever for actuating the same, a fuel pump for each of said cylinders, a shaft

mounted on said engine, tapered cams keyed to said shaft, said pump having a piston engaging one of the cams, said push rod engaging the other of the cams, and means for simultaneously operating said cams for varying the stroke of the plunger and the supply of fuel to the engine.

7. The combination with the cylinders of an internal combustion engine of an inspirator mounted on each of said cylinders and communicating with the interior thereof, a reciprocating plunger extending into said inspirator, a fuel pump delivering to said inspirator, a rotatable shaft on said engine, 10 longitudinally tapered cams keyed to said shaft and operatively connected to said plunger and pump, and slidable means associated with said cams for simultaneously varying the stroke of the plunger and the 15 supply of fuel to said inspirator.

8. The combination with the cylinders of an internal combustion engine, of an inspirator mounted on each of said cylinders and communication with the interior thereof, a 20 reciprocating plunger extending into said inspirator, a push rod operatively connected to said plunger, a fuel pump for each of said cylinders having outwardly projecting pistons, a shaft, means for rotating said shaft, 25 longitudinally adjustable cams keyed to said shaft and adapted to engage the push rods and pistons respectively for simultaneously controlling the supply of fuel to the cylinders, slidable means connected to said cams 30 for simultaneously varying the stroke of the plunger and the supply of fuel to said inspirator.

9. The combination with the cylinders of an internal combustion engine, of an inspirator mounted on each of said cylinders and communicating with the interior thereof, a reciprocating plunger extending into said inspirator, a push rod operatively connected to said plunger, a fuel pump for each of said 40 cylinders having outwardly projecting pistons, a shaft, means for rotating said shaft, longitudinally tapered cams keyed to said shaft and adapted to engage the push rods and pistons respectively, and means for simultaneously moving said cams lengthwise 45 of said shaft for varying the stroke of the plunger and the supply of fuel to the inspirator.

10. An inspirator of the class described 55 comprising a delivery nozzle having an axial bore and a tapered seat therein, a spray plug engaging said seat and having a series of spiral grooves in the wall thereof, a sleeve within said bore, a fuel passage formed 60 of the periphery of said sleeve, a fuel supply delivering to one end of said passage, a chamber communicating with the opposite end of the passage, a reciprocating plunger traversing said sleeve, and means for actuating said plunger for forcing the fuel 65

from said chamber through said grooves into the cylinder of the engine.

11. An inspirator of the class described comprising a delivery nozzle having an axial bore and a tapered seat therein, a conical 70 plug engaging said seat and having a series of spiral grooves in the wall thereof, a sleeve within said bore having a tortuous passage formed in the periphery thereof, a fuel supply delivering to one end of said passage, a 75 chamber communicating with the opposite end of said passage, said plug having converging ports connecting said chamber with said spiral grooves, a reciprocating plunger traversing said sleeve, and means for actuating said plunger for forcing the fuel 80 from said chamber through said grooves into the cylinder of an engine.

12. An inspirator of the class described comprising a delivery nozzle having an axial 85 bore and a tapered seat therein, a conical plug engaging said seat and having a series of spiral grooves in the wall thereof, a sleeve within said bore having a tortuous passage 90 formed in the periphery thereof, a fuel supply delivering to one end of said passage, a chamber communicating with the opposite end of said passage, said plug having converging ports connecting said chamber with 95 said spiral grooves, a reciprocating plunger traversing said sleeve, said nozzle having an arm projecting upwardly therefrom, a lever pivoted to said arm and operatively engaging said plunger for moving the latter in one direction, and means for moving said plunger in an opposite direction to that of said lever.

13. An inspirator of the class described comprising a delivery nozzle having an axial bore and a tapered seat therein, a conical 105 plug engaging said seat and having a series of spiral grooves in the wall thereof, a sleeve within said bore having a tortuous passage formed in the periphery thereof, a fuel supply delivering to one end of said passage, a chamber communicating with the opposite end of said passage, said plug having converging ports connecting said chamber with 110 said spiral grooves, a reciprocating plunger traversing said sleeve, said nozzle having an arm projecting upwardly therefrom, a lever pivoted to said arm and operatively engaging 115 said plunger for moving the latter in one direction, and yieldable means for moving said plunger in an opposite direction to that of said lever.

14. The combination with the cylinders of an engine, of an inspirator communicating with each of the cylinders, a reciprocating plunger in each of the inspirators for forcing the fuel into the combustion chamber, a fuel pump delivering to each of the inspirators and having a valve controlled piston extending therefrom, a shaft mounted 125 on said engine, a series of cams keyed to said 130

shaft, each of said cams adapted to engage the adjacent cam on the shaft, means for rotatably adjusting each of the cams relative to one another, means on said shaft operatively connected to said plunger for simultaneously varying the stroke of the plunger and the supply of fuel to the inspirator, and means for rotating said shaft.

15. The combination with the cylinders of an engine, of an inspirator communicating with each of the cylinders, a reciprocating plunger in each of the inspirators for forcing the fuel into the combustion chamber, a fuel pump delivering to each of the inspirators and having a valve controlled piston extend-

ing therefrom, a shaft mounted on said engine, a series of cams keyed to said shaft, each of said cams adapted to engage the adjacent cam on the shaft, said cams having aligned openings therein, pins adapted to engage said openings for adjusting each of the cams rotatively relative to one another, and movable means on said shaft operatively connected to said plunger whereby the stroke of the plunger may be simultaneously varied with the supply of fuel to the inspirator.

In testimony whereof I have hereunto set my hand.

PETER JOHNSEN.
